B. C. FOWLIE

PUMP ATTACHMENT

Filed March 5, 1924

UNITED STATES PATENT OFFICE.

BERT C. FOWLIE, OF HUNTINGTON BEACH, CALIFORNIA.

PUMP ATTACHMENT.

Application filed March 5, 1924. Serial No. 697,082.

To all whom it may concern:

Be it known that I, BERT C. FOWLIE, a citizen of the United States, residing in the city of Huntington Beach, in the county of 5 Orange and State of California, have invented new and useful Improvements in Pump Attachments, of which the following is a specification.

This invention relates generally to pumps, 10 and more particularly to pumps of the deep well type.

Since the invention may be applied with particular advantage to oil well pumps, I will describe my invention as embodied in 15 an installation of this character, though I do not intend this to be an implication that the invention is limited to such a specific application.

Oil well pumps include a plunger element 20 carried and reciprocated by sucker rods which extend through tubing to the surface, and a standing valve in the tubing below the down-stroke limit of the plunger. The floating valve stoppers ordinarily used in the 25 standing and plunger valves often fail to seat properly, especially in the presence of gas, thereby reducing the delivery of the pump considerably below normal and greatly decreasing the general efficiency of the 30 pump.

These stoppers are usually spherical owing to the absence of means for positively 35 guiding them in their movement and the consequent necessity that they have "self seat seeking" characteristics. Positively guided stoppers, in the absence of means for positively moving them, are unsuitable due to their tendency to bind with the guiding means. The presence of a comparatively 40 small amount of gas tends to roll the balls from their seats, and the resulting leakage, be it ever so slight, materially reduces the ultimate delivery of oil.

In my device, I utilize stopper stems which 45 are guided within the plunger during periods of operation, and I provide means for positively moving the stoppers. Therefore I am able to use cylindrical stoppers having flat or conical seating faces. Valve 50 stoppers of the latter type are superior to those of the spherical type in that they present more surface area both to their seats

and to the cross section of the oil column, with obviously beneficial results.

By the provision of positive valve operating means, the stoppers are moved to entirely close off the valve ports when seated, and to open up ample oil passageways during periods when it is intended that oil should pass therethrough.

The working valve is directly and positively operated by the sucker rods in their reciprocation, there being a period of lost motion between the rods and the pump plunger during which the valve is actuated. 65 The working valve, in turn, is connected to the standing valve stopper, so movement of the former effects movement of the latter. However, since the working valve has constant relative longitudinal movement with 70 respect to the standing valve when the plunger is being reciprocated, the connection between said stoppers is necessarily of a yieldable nature, and, in its broader aspects, may be considered a frictional connection.

One member of the yieldable connection is a tube secured to the standing valve stopper and extending through a usual plunger nut into the bore of the plunger. By the provision of a properly positioned Garbutt nut on the tube, the tubular member performs the function of a Garbutt attachment, since withdrawal of the plunger from the casing causes coincident withdrawal of the tubular member and its associated valve stopper, and the stopper has a connection with its cage whereby the entire standing valve is lifted from its seat in the shoe when the tubular member is raised above a certain limit.

In the following detailed description, I will fully describe a preferred embodiment of the invention, and will point out further features of novelty and objects thereof. Reference will be had to the accompanying drawings, in which—

Figure 1 is a view illustrating the lower end of a typical deep well pump installation, the working barrel, liners and standing valve shoe being shown in section, and the standing valve and plunger, with which my invention is incorporated, being shown in elevation.

Fig. 2 is an enlarged and contracted section through the pump plunger and standing

valve, certain of the parts being shown in elevation, and illustrating the positions of the various parts when the plunger is at the limit of its down stroke.

5 Fig. 3 is a view similar to Figure 2 but showing the parts in the position they assume during the up stroke of the plunger.

Fig. 4 is a horizontal section on line 4—4 of Figure 3.

10 Fig. 5 is an enlarged horizontal section on line 5—5 of Figure 2.

Fig. 6 is an enlarged vertical section on line 6—6 of Figure 2; and

15 Fig. 7 is a horizontal section on line 7—7 of Figure 6.

In the drawings, numeral 10 designates a pump plunger which is adapted to be reciprocated by sucker rods 13 through liners 11 of barrel 12. At the lower end of barrel 20 12 is the usual shoe 14 within which is seated a standing valve 15. Valve 15 is made up of lower member 16 and cage 17, which are threadably joined by valve seat bushing 18, and valve stopper 19. The upper face or seat of bushing 18 may be provided with an annulus 20 of soft metal, or the like, to insure a fluid tight joint between seat and stopper. The body 21 of stopper 19 is cylindrical and preferably, though not 30 necessarily, has a sliding fit between cage posts 22. Grooves 23 in the cage head or crown 24 provide oil ways from the interior of the cage to the barrel bore 25 above the standing valve. A tube 26, coaxial with 35 valve 15 and plunger 10, has a sliding fit through head bore 24^a and is threaded into the stopper extension 27, the latter preferably being squared or otherwise suitably mutilated to receive a wrenching tool.

40 Tube 26 extends upwardly through the clearance bore of a usual plunger nut 28, and thence into the bore 29 of the plunger where it terminates in a Garbutt nut 30. Nut 30 is so positioned with respect to the

45 longitudinal extent of the plunger that, during the normal stroking of the pump, there is no coaction between nuts 28 and 30. However, when the plunger is withdrawn, nut 28 picks up nut 30 thus lifting tube 26 and stopper 19. Stopper extension 27, through its engagement with the lower face of cage head 24, then withdraws valve 15 from shoe 14. Thus the assembly just described is adapted to perform the function 50 of the well known Garbutt attachment. My assembly, however, differs from the usual Garbutt attachment in the feature of joining the rod to the standing valve stopper rather than to the valve cage.

60 Attached by bushing 31 to the top of plunger 10 is the blind valve 32 which is provided with head 33, the latter being centrally bored at 34. The lower head face 35 forms the seat of the working valve, while the valve stopper 36, which is adapted to

intermittently seat on face 35, is threaded on the lower end of the longitudinally fluted stem 37. This stem extends through bore 34 and terminates in a head 38 above the valve cage, and the head preferably has a square portion 38^a for receiving wrenching tools. 70

Sucker rod 13 is threaded into head 38 and is adapted to reciprocate the stopper 36 and, by thus causing alternate engagement of stopper 36 and head 38 with opposite ends of valve head 33, the sucker rod also serves to reciprocate the plunger. Thus, in effect, rod 13 has a lost motion connection with the plunger, and valve 32 is opened and closed during periods of such lost motion. The upper face of head 33 has radial grooves 39 to provide for the passage of oil from between the flutes of stem 37 to the pump barrel above the plunger during the down stroke of the latter. 80

A longitudinally fluted rod 40 is threaded into the squared base 41 of stopper 36 and extends downwardly through the bore of tube 26. Rod 40 and tube 26 thus form a telescopic and yieldable connection 90 between valve stoppers 19 and 36, rod 40 being adapted to move longitudinally through the tube during the stroking of the plunger.

Rod 40 terminates in a ground taper 42 and a fluted tip 43. A centrally apertured piston valve 44 is adapted to slide longitudinally along tip 43, the movement of the piston in one direction being limited by the taper 42 and in the other direction by retention nut 45 threaded on the extremity of the tip. The tubular piston 44 preferably has a snug sliding fit within the bore of tube 26, and the upper end of the piston is provided with a conical valve seat 46 which is complementary to the taper 42. A relief port 47 is provided in tube 26 at a point below the down stroke limit of the piston. The upper, open end of the tube and port 47 provide longitudinally spaced oil passageways into the tube bore. The fluted rod is adapted to be reciprocated between these passageways and the flute grooves provide for communication therebetween when the piston valve is open. 110

I will now describe the operation of the pump. Assuming that rods 13 are at the limit of their up stroke, the plunger and standing valve parts will be in the relative position of Figure 3, and a charge of oil will be present within the bore of the plunger and within the pump barrel below the plunger. Tube 26 will be filled with oil which has entered through port 47 and from the top of the tube between the flutes of rod 40. The passageways formed by the grooving or fluting of rod 40 and, further defined by the internal peripheral face of tube 26, are also filled with oil, and it may be well to state at this time that by reason of these 120 125 130

oil-ways and the presence of oil therein, the contacting faces of the rod and tube may be kept constantly lubricated.

At the start of the sucker rod's down stroke, lost motion occurs between said rod and the plunger due to the fit of the plunger within the barrel and to the column of oil beneath said plunger. At the end of this period of lost motion, valve 32 has been positively opened and head 38 has come into contact with valve face 33, so that subsequent downward movement of the sucker rods positively moves the plunger downwardly. Also during the period of lost motion, rod 40, due to its connection with stopper 36, is positively moved downwardly through tube 26. At the start of the rod's movement, taper 42 coacts with piston seat 46, due to the supporting oil column beneath the piston, to close off communication between the oil-ways of the rod and the bore of tube 26 below the rod. Continued downward movement of the rod then presses downwardly the column of oil confined within the tube between the piston and stopper, and the oil column, in turn, presses downwardly upon and acts against the top of stopper 19, where the latter is exposed to the column within the tube, and forces said stopper down into firm seat. After the stopper is thus seated rod 40 continues in its downward movement within the tube until the sucker rods and plunger are at the end of their down-stroke, relief port 47 allowing sufficient escape of oil from the tube between piston and stopper to allow for this relative movement between rod and tube; the diameters of relief port 47 and of the tube bore being proportioned to allow the passage of oil from out the tube with sufficient velocity to prevent such back pressure as is set up in the tube from resisting the down movement of the rod to an undesirable degree.

As soon as valve 32 is fully opened and valve 15 fully closed (Figure 2), the continued movement of the plunger passes the oil from above valve 15 through the following path: bore of plunger nut 28, plunger bore 29, grooves of stem 37, and then through grooves 39 to the pump barrel bore at a point above the plunger.

As rods 13 start their up-stroke, valve 32 is positively and tightly closed due to the relative longitudinal movement of the plunger and stopper 36 (the plunger temporarily being held stationary by reason of its fit within the barrel and by reason of the oil column above it), and rod 40 is drawn upwardly through tube 26. The initial upward movement of the rod causes relative longitudinal movement between tip 43 and piston 44 (nut 45 limiting the extent of this movement) so the following passageway between the grooves of rod 40 and the bore of tube 26 below the piston is opened up;

radial grooves 45^a in nut 45, grooves 43^a in tip 43, and the bore of the tubular piston.

By reason of this passageway, the rod may be drawn upwardly through the tube without undue resistance from the oil within the latter, but due to the relatively restricted diameter of port 47, which port now acts as an inlet, sufficient suction is set up within the tube to cause the tube to follow along with the rod, thus raising the tube and its stopper to the position of Figure 3. However, the suction is not sufficiently great to overcome the frictional hold between shoe 14 and valve 15, so, as soon as stopper head 27 strikes cage head 24, the tube and lower stopper come to rest while the plunger and rod 40 continue in their upward movement.

During the up stroke of the plunger the oil column above it is lifted by reason of closed valve 32; while oil is drawn through valve 15 into the pump barrel beneath the plunger, grooves 23 allowing the passage of oil from within cage 17 to said barrel.

I wish it to be understood that the accompanying drawings and foregoing specification are to be considered merely as illustrative of and not restrictive on the broader claims appended hereto, for various changes in structure, design and arrangement may be made without departing from the spirit and scope of these claims.

I claim:

1. In a pump, a relatively movable fluid pumping element, a relatively stationary standing valve having a movable valve stopper, and fluid pressure means operated by the movable element and adapted to move the stopper.

2. In a pump, a standing valve having a valve stopper adapted to be seated by downward pressure exerted thereon, a reciprocating plunger, a reciprocating element for operating the plunger, and means operated by said element by virtue of its reciprocation and adapted to move the stopper; said means including a tubular member secured to the stopper, a rod carried by the element and adapted to be reciprocated thereby within the tubular member, there being a passageway in the tubular member for allowing restricted passage of fluid into and out of the tubular member between the rod and stopper, said rod, on the down-stroke of the element, being adapted to press the fluid beneath it downwardly upon the stopper and thereby seat the stopper.

3. In a pump, a standing valve having a valve stopper adapted to be seated by downward pressure exerted thereon, a reciprocating plunger, a reciprocating element for operating the plunger, and means operated by said element by virtue of its reciprocation and adapted to move the stopper; said means including a tubular member secured to the stopper, a rod carried by the element and

adapted to be reciprocated thereby within the tubular member, a piston on the rod and fitting the bore of the tubular member, there being a passageway in the tubular member 5 for allowing restricted passage of fluid into and out of the tubular member between the piston and stopper, said piston, on the down-stroke of the element, being adapted to press the fluid beneath it downwardly upon the 10 stopper and thereby seat the stopper.

4. In a pump, a standing valve having a valve stopper adapted to be seated by downward pressure exerted thereon, a reciprocating plunger, a reciprocating element for 15 operating the plunger, and means operated by said element by virtue of its reciprocation and adapted to move the stopper; said means including a tubular member secured to the stopper, a rod carried by the element and 20 adapted to be reciprocated thereby within the tubular member, said rod having passageways adapted to allow the passage of fluid longitudinally therealong, a movable piston on the rod and fitting the bore of the 25 tubular member, there being a passageway in the tubular member for allowing restricted passage of fluid into and out of the tubular member between the piston and stopper, said piston, on the down-stroke of the element, being adapted to close the rod passageways and to press the fluid beneath it 30 downwardly upon the stopper and thereby seat the stopper.

5. In a pump, a standing valve having a 35 valve stopper adapted to be seated by downward pressure exerted thereon, a reciprocating plunger, a reciprocating element for operating the plunger, and means operated by said element by virtue of its reciprocation and adapted to move the stopper; said 40

means including a tubular member secured to the stopper, a rod carried by the element and adapted to be reciprocated thereby within the tubular member, there being a passageway in the tubular member for allowing 45 restricted passage of fluid into and out of the tubular member between the rod and stopper, said rod having passageways adapted to allow the passage of fluid longitudinally therealong, a valve on the rod adapted to be moved alternately to close and open 50 said passageways when the rod is reciprocated, and said rod, on the down-stroke of the element, being adapted to press the fluid beneath it downwardly upon the stopper and thereby seat the stopper.

6. In a pump, a standing valve having a valve stopper adapted to be seated by downward pressure exerted thereon, a reciprocating plunger, a reciprocating element for 55 operating the plunger, and means operated by said element by virtue of its reciprocation and adapted to move the stopper, said means including a tubular member secured to the stopper and having longitudinally spaced fluid passageways, a fluted rod carried by the element and adapted to be reciprocated thereby within the tubular member, said rod extending between said passageways and the 60 flute grooves providing for communication between said passageways, and a valve movable to open and close the ends of the 65 grooves to interrupt the communication and operated by virtue of the reciprocation of the rod within the tubular member.

In witness that I claim the foregoing I have hereunto subscribed my name this 21 day of February 1924.

BERT C. FOWLIE.
